UNITED STATES PATENT OFFICE.

DAVID BAKER, OF PHILADELPHIA, PENNSYLVANIA, ASSIGNOR OF ONE-THIRD TO
JOHN J. SHANNON, OF BIRMINGHAM, ALABAMA, AND ONE-THIRD TO LADD &
BAKER, INCORPORATED, A CORPORATION OF PENNSYLVANIA.

MOLD FORMING AND CASTING APPARATUS.

1,049,644.

Specification of Letters Patent.

Patented Jan. 7, 1913.

Application filed August 16, 1910. Serial No. 577,512.

To all whom it may concern:

Be it known that I, DAVID BAKER, a citizen of the United States, residing at Philadelphia, in the county of Philadelphia and 5 State of Pennsylvania, have invented certain new and useful Improvements in Mold Forming and Casting Apparatus, of which the following is a specification, reference being had therein to the accompanying drawing.

In the casting of pig iron, where the molten metal as it flows from the furnace, is poured directly into the molds, the cast product is usually very irregular in chemical 15 composition, such irregularity being due to the absence of opportunity for the metal to mix to any extent in the hearth of the furnace before it is drawn off.

It is one of the aims of my invention to 20 avoid this objection and secure a pig iron of uniform composition in the cast, and at the same time provide for the casting of the pigs in a continuous and expeditious manner, and so that they will possess a natural fracture, such as is characteristic of sand castings. With these ends in view, I propose to handle an entire cast from the furnace, so far as possible in one ladle or receptacle, or in as large units as feasible in 25 order to secure a thorough and complete mixing of the metal before it is poured into the molds; and I propose, further, in accordance with my invention, to employ for the casting of the metal, an apparatus of 30 improved form and construction embodying, in combination, a series of mold receptacles, means for supplying mold material—preferably sand—thereto, means for forming mold cavities in the material, and means 35 for supplying casting material to the mold cavities, these several means coöperating with each other in such manner that the castings will be produced successively and continuously.

In its more specific embodiment, the apparatus of the present invention comprises 40 a series of traveling mold receptacles; a holder or hopper to contain the mold material—in the present instance, sand—which hopper is arranged to discharge into the mold receptacles traveling beneath the same; a mold cavity forming device—in the present instance, a wheel formed with projections corresponding to the form of the mold

cavity and the castings to be produced—55 which wheel is arranged to coöperate with the sand-filled mold receptacles as the same travel past the wheel and to form the mold cavities therein; and a reservoir or receptacle to contain the casting material—in the 60 present instance—molten metal—which receptacle is arranged above the traveling molds and disposed to discharge the metal successively into the mold cavities. Means are provided for separating the castings 65 from the sand, such means being preferably in the form of a screen onto which the traveling mold receptacles discharge the sand and castings, the sand falling through the screen and the castings sliding off the screen. 70 The separated sand is, by suitable means—for instance, a conveying mechanism—conducted back to the hopper to be used again.

In the accompanying drawings: Figure 1 is a top plan view of my improved apparatus. Fig. 2 is a side elevation of the same. Fig. 3 is an end elevation as viewed in the direction of the arrow in Figs. 1 and 2. Fig. 4 is an elevation on an enlarged scale, partly in section, of the receiving end of the series 80 of mold receptacles, the supply hopper for the molding material, and the mold cavity forming device. Fig. 5 is a transverse sectional elevation through the same on the line *a—a* of Fig. 4 as viewed in the direction of the arrow in said figure.

Referring to the drawings: my improved apparatus comprises as its main features, an endless chain of connected mold receptacles 1; a hopper or holder 2, in which the 90 mold material is placed, and arranged to discharge successively into the receptacles traveling beneath the same; a mold cavity forming device 3 arranged above the chain of mold receptacles in position to coöperate 95 with the sand-filled receptacles after they leave the hopper to form mold cavities therein; a reservoir or holder 4 for the molten metal arranged above the chain of mold receptacles and adapted to supply molten 100 metal to the mold cavities formed by the mold forming device; a screen 5 arranged at the end of the chain of mold receptacles, onto which the receptacles successively dump their contents, and by which the sand is 105 separated from the castings; and a conveying mechanism 6 leading from the discharge end of the chain of receptacles back to the

2
hopper and acting to conduct the separated sand back and discharge the same into the hopper.

The endless chain 1 of mold receptacles 5 consists of a series of trays or pans 1^a jointed together at their edges and flexibly connected by links 1^b, at the junction of which are arranged rollers 1^c adapted to engage between the teeth of two pairs of carrying 10 wheels 7 and 8, over which the chain of receptacles passes at opposite ends. The carrying wheels 7, at the receiving end, are carried by a shaft 7^a mounted in suitable bearings 7^b sustained by standards 7^c. The 15 carrying wheels 8, at the opposite end, are similarly carried by a shaft 8^a mounted in bearings 8^b in fixed standards 8^c, the end of which shaft is provided with a driving gear 8^d engaged by a pinion 8^e on a second 20 shaft 8^f, which latter may be driven from any suitable source of power so as to rotate the carrying wheel 8 and cause the chain of receptacles to travel at the upper side in the direction of the arrow in Fig. 2. In 25 their travel, the receptacles on the upper chain are sustained on fixed rails 10 extending longitudinally between the pairs of carrying wheels, so that the receptacles will be properly guided and supported in receiving the sand and molten metal. At the underside of the chain, the receptacles in their travel are supported by longitudinal rails 11, which act to prevent the same from sagging.

30 The hopper 2 for the mold material, in the present instance sand, is suitably supported in fixed position above the chain of mold receptacles adjacent the carrying wheels 7, and has its lower end contracted to form a discharge spout 2^a through which the sand will be supplied to the mold receptacles as the latter travel past the spout, which latter may be provided with a suitable gate 2^b to control the flow of the sand.

35 The mold cavity forming wheel 3 is carried by a shaft 3^a mounted to rotate freely in bearings 3^b sustained by standard 3^c extending upwardly at opposite sides of the chain adjacent the discharge spout 2^a of the sand hopper. This wheel is so disposed that its mold forming projections 2^c will enter the sand-filled mold receptacles as they pass in succession beneath the wheel, the travel of the receptacles acting to rotate the wheel 40 and causing the projections thereon to displace the sand and form mold cavities in the receptacles, corresponding to the form of the projections on the wheel and the form of the castings to be produced.

45 The reservoir or holder 4 for supplying molten metal to the mold cavities may be of any suitable form, and arranged in any suitable manner to supply the metal to the mold cavities. I prefer to employ for this purpose a ladle of large capacity so that

a great proportion of the cast of a furnace may be handled at one time, this insuring a thorough mixture of the metal and a uniform condition in the cast product. This ladle is adapted to be supported on a track or way 4^a extending over the chain of receptacles, and is mounted as shown on a carrying car so that it may be tipped to pour its contents. The metal from the ladle is received in a longitudinally extending trough 4^b connected at its inner end to the track structure, or other suitable fixed support, and supported at its opposite end by means of a prop 4^c, so that its discharge end will terminate close above the molds traveling beneath, thereby insuring the passage of the metal from the trough to the molds without waste as the molds travel in succession past the trough.

From the construction described, it will be seen that as the mold receptacles travel from the receiving to the discharging end of the chain, they will be first filled with sand from the hopper. The sand-filled receptacles will then have mold cavities formed therein by the forming wheel, and finally the cavities will be supplied with molten metal from the ladle. In order that after the casts have been thus formed they may be discharged from the molds, and the sand separated for further use, the screen 5, before alluded to, is employed. This screen is arranged in an inclined position at the discharge end of the chain of mold receptacles, so that as the chain passes over the carrying wheels 8 at that end, the receptacles in tipping will discharge the castings and sand onto the screen, and the castings will slide down the screen, while the sand will fall through the same and may be received in any suitable manner, as for instance in a pit 13 beneath the screen. In order to return the separated sand to the hopper for use again, the conveying mechanism 6, before alluded to, is employed. This mechanism may be of any suitable form or construction adapted for the purpose in view. I prefer to employ a transversely acting endless flight 14 leading from the pit to a longitudinally extending belt conveyor 15. This conveyor 15 discharges at its opposite end into the lower portion of a vertically arranged chain of buckets 16, which at its upper end delivers into a spout 17 leading to the hopper 2. By this means, the separated sand is returned to the hopper for use again in the formation of the molds.

It will be understood of course that suitable means may be employed for cooling the castings; and also for cooling the sand and giving the same the proper moisture for use in the molding process.

I have in the accompanying drawings illustrated my invention in the form which I prefer to adopt, but it will be understood

that the details and form of the different coöperative mechanisms may be changed within the skill of the mechanic without departing from the limits of the invention, 5 provided the operation will be substantially as indicated as above; and it will be understood that my invention is not to be limited to any particular form or construction of the parts except in so far as such limitations 10 are specified in the claims. It will be further understood that while I have referred to my apparatus as being useful particularly in the casting of pig-iron, it may be used to advantage for casting other materials and for forming casts of other forms.

Having thus described my invention, what I claim is:—

1. In an apparatus of the character described, the combination of a traveling endless chain of jointed mold pans, a track or way on which said pans are supported at one point in their travel, a mold-material supplying hopper provided with a spout arranged over the supported pans to discharge 25 therein in succession as the pans travel past the spout, and a mold-cavity forming device arranged over the supported pans and acting to automatically form cavities in the filled pans in succession as they pass thereunder.

2. In an apparatus of the character described, the combination of an endless chain of jointed mold pans, vertical supporting wheels over which said chain passes at opposite ends and around which the chain travel from its receiving toward its discharging end, means for forming castings in the pans on the upper side of the chain, and a downwardly inclined separating 40 screen arranged at the discharge end of the chain with its receiving end in position to receive the castings and mold material discharged at the down-going end of the chain.

3. In an apparatus of the type described, 45 the combination of a traveling chain of mold pans, a hopper for the mold material adapted to discharge into said pans, means for forming mold cavities in the filled pans,

means for supplying casting material to the cavities, a screening device at the discharge 50 end of the chain in position to receive the castings and mold material discharged from the mold pans, a transverse conveyer beneath the screen to receive the mold material from the screen and a longitudinally 55 extending conveyer in position to receive the mold material from the first conveyer and operating to deliver the same to the hopper.

4. In an apparatus of the type described, 60 the combination of a chain of traveling mold pans, a hopper for the mold material adapted to discharge into the mold pans, means for forming mold cavities in the 65 filled pans, means for supplying casting material to the cavities, means at the discharge end of the chain for separating the castings from the mold material, a transversely acting conveyer to receive the mold material, a longitudinally arranged conveyer to receive the material from the first 70 conveyer and carry it toward the receiving end of the chain of mold pans, an elevating conveyer into which the longitudinally acting conveyer discharges, said elevating conveyer arranged to carry the mold material 75 upwardly, and a spout leading from said elevating conveyer into the hopper.

5. In an apparatus of the character described, the combination of a freely rotatable wheel provided with mold cavity forming projections, a series of mold receptacles movable past said wheel, and means for supplying mold material to said receptacles before they reach the wheel; whereby in the 80 travel of the receptacles past the wheel, the latter will be rotated and the forming projections thereon will be caused to successively enter the receptacles and form molding cavities in the mold material. 90

In testimony whereof I have affixed my signature in presence of two witnesses.

DAVID BAKER.
